(57) **CLAIM**

The ornamental design for a gaming machine, as shown and described.

DESCRIPTION

FIG. 1 is a front perspective view of a gaming machine showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines depicting the remainder of the gaming machine illustrates environmental structure and form no part of the claimed design. The curved oblique line shading represents that the surface is curved and that it is transparent, translucent, highly polished or reflective.
